W. F. HAMES,
TONE INDICATING DEVICE FOR VIOLINS.
APPLICATION FILED OCT. 4, 1920.

1,392,151.

Patented Sept. 27, 1921.

William F. Hames Inventor

Howard E. Barlow
Attorney

UNITED STATES PATENT OFFICE.

WILLIAM F. HAMES, OF PROVIDENCE, RHODE ISLAND.

TONE-INDICATING DEVICE FOR VIOLINS.

1,392,151.

Specification of Letters Patent. Patented Sept. 27, 1921.

Application filed October 4, 1920. Serial No. 414,595.

To all whom it may concern:

Be it known that I, WILLIAM F. HAMES, a citizen of the United States, residing at Providence, in the county of Providence and State of Rhode Island, have invented certain new and useful Improvements in Tone-Indicating Devices for Violins, of which the following is a specification.

This invention relates to an improved tone-indicating device to facilitate the tuning of stringed instruments, and has for its object to provide such a device which may be connected to a stringed instrument, such for instance as a violin, viola, cello, bassviol, or other similar instrument, whereby the tensions of the different strings of the instrument, may be visibly indicated.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:

Figure 1 is a top view illustrating my improved tone-indicating device as applied to the tail-piece of an instrument.

Fig. 2 illustrates the invention shown in Fig. 1 with the top plate of the frame removed to better show the operation of the spring-tension arms mounted thereon.

Fig. 3 is a transverse sectional elevation on line 3—3 of Fig. 2.

Fig. 4 is a transverse sectional elevation on line 4—4 of Fig. 2.

Fig. 5 is a view of the frame member in extended position, as cut from sheet stock.

It is found by instructors who teach the violin and other similar musical instruments, such as for instance the viola, cello, bassviol, and the like, very difficult, particularly where the pupil has not developed an acute musical ear, to teach the pupil to tune the different strings accurately and to bring them up to concert pitch and to adjust them to tune with each other. Therefore to assist the pupil in this respect I have provided a device which will visibly indicate when the tension of the different strings is sufficient to bring them to the proper pitch; and the following is a detailed description of one means by which this result may be accomplished:

The frame-member of my improved tone

indicator is preferably constructed of sheet metal and cut from sheet stock in substantially the form illustrated in Fig. 5, which is then folded back upon itself providing an upper plate 10 and a lower plate 11 which are spaced apart and connected together at the fold 12.

The lower plate 11 is provided with a pair of ears 13 which are adapted to extend around beneath the tail-piece 14 of the instrument, and these ears are provided with holes through which a binding bolt 15 is passed for the purpose of clamping this frame member upon the tail-piece.

The upper and lower plates of this frame-member are spaced apart and through them I have passed two pins or posts 16 and 17 also a stop pin 18.

In order to provide means for visibly indicating the amount of tension on each individual string, I have provided a set of four arms 19, 20, 21 and 22, each formed of a wire having a different degree of resistance to compensate for the different degrees of tension required in the different strings to bring them to the proper pitch. The arms 19 and 20 are coiled about the pin 16 and their ends 23 and 24 are fulcrumed against the rear pin 17 while the arms 21 and 22 are coiled about the pin 17 and their ends 25 and 26 are fulcrumed against the stop pin 18.

The free end of each of these arms is bent around to extend over the edge of the upper surface of the plate 10, and is brought to a sharp point and this plate is provided with graduations or tone setting points as indicated at *a*, *d*, *e*, and *g*, which are the names of the different strings of the instrument.

Each of these spring tension arms is shown as being provided with a loop 27 into which the end of each of the respective connector members 28 is secured, the outer ends of which connector members are provided with eyes 29 into which the respective strings *a*, *e*, *d*, and *g* are inserted.

It will be noted that my improved tone-indicating device is complete in itself, all being mounted in the frame which is adapted to be readily connected to the tail-piece of an instrument and perform its full function without in any way injuring or changing any portion of the instrument, and the device may be as readily removed from the instrument after it has served its useful purpose, restoring the same to its original effectiveness.

In the operation of the device, it is only necessary to connect the different strings to the different extension members 28, then tension is applied to the different strings by means of the usual keys, sufficient to swing the ends of the respective tension arms up to their different indicating points as shown on the face-plate, which result visibly indicates that the tension of the individual strings is at concert pitch.

The device is extremely simple and practical in construction and effective in its operation and by its use unskilled musicians may readily and accurately adjust different strings of instruments to concert pitch and in tune with each other.

The foregoing description is directed solely toward the construction illustrated, but I desire it to be understood that I reserve the privilege of resorting to all the mechanical changes to which the device is susceptible, the invention being defined and limited only by the terms of the appended claims.

25 I claim:

1. A tone-indicator for stringed instruments comprising a set of spring arms mounted on posts on the tail piece of an instrument, means whereby the different strings of the instrument may be connected to said arms, and means on the device for visibly indicating when said arms have been moved by the tension of the strings sufficiently to bring the strings up to their proper pitch.

2. A tone-indicator for stringed instruments comprising a set of spring arms mounted to swing substantially parallel to the plane of the sound board of the instrument on the tail-piece of an instrument, said arms being adapted to have the different strings connected thereto, and means to visibly indicate the pitch of each string caused by the movement of each arm under tension of its string.

3. A tone-indicator attachment for stringed instruments comprising a frame supported on the tail-piece of an instrument, a set of spring arms carried by said frame and to which the strings of the instrument are to be connected, means for readily securing the frame to the tail-piece, and means on said frame for visibly indicating by the position of each spring member when the tension of its string is at concert pitch.

4. A tone-indicator attachment for stringed instruments comprising a frame supported on the tail-piece of an instrument, a set of spring arms mounted on said frame to swing substantially parallel to the plane of the sound board of the instrument and to which the strings are to be

connected, clamping means on said frame for readily connecting the same to the tail-piece, and means on said frame for visibly indicating by the position of each spring arm when the tension of its string is at concert pitch.

5. A tone-indicator for stringed instruments comprising a plurality of spring arms of different degrees of resistance under tension and each adapted to have a string of the instrument connected thereto, indicating means on said arms to indicate the tension on each of said strings.

6. A tone-indicator for stringed instruments comprising a frame, a plurality of posts secured on the frame, spring arms on the posts and extending laterally therefrom, each of said arms being adapted to have a string of the instrument secured thereto.

7. A tone-indicator for stringed instruments comprising a frame, a plurality of posts secured on the frame, spring arms on the posts and extending laterally therefrom, each of said arms being adapted to have a string of the instrument secured thereto, an indicator on each of said arms, and a standard point with which each of said indicators coöperates.

8. A tone-indicator for stringed instruments including a frame formed of a piece of sheet metal folded on itself to provide upper and lower plates, posts between the plates, spring members looped around said posts and having outwardly extending arms to each of which a string of the instrument may be connected, setting points on the outer surface of said top plate, and indicators one on each of said arms to coöperate with said setting points.

9. A tone-indicator for stringed instruments comprising upper and lower plates, posts between said plates and maintained in position thereby, spring arms extending laterally from said posts to each of which a string of said instrument may be connected, setting points on the top plate, and means on the arms to coöperate with the setting points.

10. A tone-indicator for stringed instruments comprising upper and lower plates, posts between said plates and maintained in position thereby, spring arms extending laterally from said posts and each having a different degree of resistance when under tension, each of said arms being adapted to have a string of said instrument secured thereto, setting points on the top plate, and means on the arms to coöperate with the setting points.

In testimony whereof I affix my signature.

WILLIAM F. HAMES.
